(57) **CLAIM**

The ornamental design for a bottle brush, as shown and described.

DESCRIPTION

FIG. 1 is a front view of a bottle brush showing our new design;

FIG. 2 is a rear view thereof;

FIG. 3 is a side view thereof;

FIG. 4 is an opposite side view thereof;

FIG. 5 is a top view thereof;

FIG. 6 is a bottom view thereof;

FIG. 7 is a bottom perspective view thereof; and,

FIG. 8 is a top perspective view thereof.

The broken lines illustrate environmental features and form no part of the claimed design.
